UNITED STATES PATENT OFFICE.

FRANK E. SMITH, OF SCOTTDALE, PENNSYLVANIA.

ENDLESS-BELT CARRIER.

REISSUED

Application filed May 8, 1922. Serial No. 559,241.

To all whom it may concern:

Be it known that I, FRANK E. SMITH, a citizen of the United States, residing at Scottdale, in the county of Westmoreland and State of Pennsylvania, have invented 5 certain new and useful Improvements in Endless-Belt Carriers, of which the following is a specification.

My invention relates to the art of endless belt carriers, and refers particularly to the construction of the roller supports for the carrying belt.

In this art, it is customary to support the carrying belt by a continuous series of either 15 single or multiple rollers having their axial centers arranged transversely across the carrying strand. In the case of single rollers, they are customarily horizontal, while some or all of the multiple rollers of each trans- 20 verse series are usually arranged at varying inclinations at each side of the longitudinal center of the belt, to provide for "dishing."

In my invention I have provided means 25 for mounting the carrying rollers whereby they may be erected to normal operative supporting position underneath the belt, or whereby one or all of the rollers of each 30 series may be lowered for removal, adjustment, or repair. Also, means for properly mounting and supporting the bearing members for the several cross shafts of the rollers, means tending to a minimum of friction, 35 means for lubricating the several bearing members, and other features hereinafter more fully described.

The objects in view, in addition to those noted, are to provide a simple, effective, and economical construction capable of giving 40 the best results in continuous use and which may be lowered or erected without stoppage of the belt.

Certain preferred embodiments of the invention are illustrated in the accompanying drawings, in which:

45 Fig. 1 is a cross sectional view showing three carrying rollers mounted in their several bearings and carried by their common tilting shaft;

50 Fig. 2 is a partial similar view showing a modified construction of supporting brackets;

Fig. 3 is a similar view showing five car-

rying rollers with a corresponding arrangement of supports therefor;

Fig. 4 is an enlarged sectional detail of 55 one of the supporting brackets for the roller shaft bearings;

Fig. 5 is a view of the bracket in elevation;

Fig. 6 is a sectional detail view of one of 60 the valve controlled branch connections of the lubricating pipe;

Fig. 7 is a partial sectional view similar to Fig. 4 showing a modified construction of 65 supporting bracket;

Fig. 8 is a sectional detail view of one of the friction reducing bearings for the roll spindle;

Fig. 9 is a cross sectional view through the cross supporting shafts showing the 70 roller supporting bracket in erected position thereon;

Fig. 10 is a similar view showing the bracket and roller in lowered position;

Fig. 11 is a perspective detail view of 75 one of the detachable supporting brackets like that of Fig. 5, from the rear;

Fig. 12 is a longitudinal sectional view showing a further modification utilizing independent or individual brackets for each 80 roller respectively, providing for individual adjustment of each roller;

Fig. 13 is a cross section on the line XIII—XIII of Fig. 12;

Fig. 14 is a partial plan view of Fig. 12. 85

Referring to Fig. 1, showing a series of rollers A, B and B arranged in conventional series for carrying a belt conveyor in trough shape, the several rollers being mounted on a rock shaft 2 by outermost compound 90 brackets b, b, and inner compound brackets, a, a, respectively. Each bracket is provided with a hub 3 embracing the shaft 2 and secured thereto in fixed alignment by securing pins or rivets 4, as in Fig. 7.

The rollers A and B are of well known construction, comprising an outer cylindrical or tubular shell 5 carried by the endmost flanges of hubs 6 upon shafts or spindles 7. These, in turn, are rotatably mounted by 100 their terminals 8 in the ball or roller bearing casings 9 (Fig. 8) by means of rolling members, as balls 10, engaging inner and outer bushings 11, 12, of the spindle and cas-

ing respectively, as will be readily understood. Bushing ring 11 is preferably clamped tightly on the coniform terminal 8 of shaft 7 by a nut 13 of its threaded extension 14, as shown, so that the shaft and its bushing are free to revolve in transmitting moving support to the conveyor belt C. The interior of each inner casing 9 is supplied with lubricant, as grease, by tubular conduit 15 connected with a main supply pipe 16, and the outermost bearing casings are lubricated directly by grease cups 17, as in Figs. 1 and 7.

The several hubs 3 of brackets *a* and *b* are fixedly mounted in alignment on their supporting rock shaft 2, as stated, and shaft 2 is tiltingly mounted in end bearings 18, 18, carried by the outermost supporting members, as channels 19, of the supporting structure. A supporting cross member, which may be in the form of a shaft 20, is similarly mounted on the framework adjacent to each such shaft 2 on the same general level for each transverse roller, or set of rollers.

Each hub 3 has an extended supporting bracket arm 21 provided with a terminal open sided bearing 22, for supporting engagement on such member 20, when the brackets are erected, as in Figs. 9 and 13. In such position, with the belt supported upon the rollers, and running in the direction indicated by the arrow, the brackets will normally press towards the cross member 20, but for positively securing them in lowered position, I use a removable pin 23 inserted through registering holes in the bracket bearing and cross member.

The main lubricant supply pipes 16, usually one for each set of bearings, lie across the bearing brackets and extend towards one side, where each is provided with a closing terminal cap 24, and adapted for connection with a grease gun or the like. Each main pipe 16 is connected as at 25 by a suitable union coupling, with a semi-flexible tube 26 having an elastic loop 27 to facilitate communicating connection by conduit 15 with the bearing. A cock or valve 28 is preferably inserted in the branch line 26 at any suitable point, as shown, Fig. 7, for controlling the circulation to one or both bearings.

In the construction shown in Fig. 1, the outermost hubs 3 are provided with upwardly extending brackets 29 having flanged attaching faces for bolting thereto the supplemental bearing brackets 30 carrying the outer bearing casings 9. Brackets 30 are bifurcated at their upper ends, providing a pair of side cheeks having inwardly open sockets 31 for reception of the lugs 32 extending from opposite sides of the bearing casings 9.

Lugs 32 are preferably knife-edges at their lower supporting portions for equal

balancing, and enter the slots 31 with slight clearance, as shown.

The intermediate hubs 3 also extend upwardly and are of compound construction, as shown, whereby to provide a bearing support for the inner downwardly sloping end of the outer roller spindle, and a separate bearing support for the end of the middle roll spindle. To this end, hub 3 is extended upwardly integrally by extension 3^a 75 and is similarly bifurcated and slotted at 31 for supporting the lugs 32 of the inner bearing casing 9 of the outer roller.

Mounted on the inner side of extension 3^a is a supplemental bracket 33, similarly 80 bifurcated and slotted, and provided with side cheek lugs 34 embracing the extension 3^a and engaging lugs or bolt terminals 35. The bracket 33 extends downwardly along the inner face of extension 3^a, providing 85 abutting engagement therewith, so as to firmly support the roller spindle bearing.

The construction as shown in Fig. 1 provides a similar bearing for each end of the roller spindle, of right and left hand form, 90 so that the middle horizontal roller is thus carried at its proper level between the outer upwardly sloping rollers.

By this arrangement, the entire series of 95 rollers may be tilted backwardly on shaft 2 in receded position below the belt for adjustment, removal, or insertion of any individual roller or its bearings without interference or stoppage of the belt. Thus, either end roller B may be disconnected by 100 removal of bracket 30 and disconnection of branch lubricant pipe 26, permitting the 105 lugs 32 of rear bearing casing 9 to be withdrawn from openings 31. Likewise, by removing one of the brackets 33, the middle 110 roller A may be withdrawn without removing the other bracket, first having disconnected the lubricant pipes as described.

If desired, one of the inner supporting 115 bracket extensions may be made integral, as at 3^b, with oppositely extending bifurcated and slotted cheeks for supporting engagement with the roller bearing casings, as shown at the left side of Fig. 2. The other 120 side, being separable as shown and as just described, provides for separability of either roller in lowered position of the brackets.

In Fig. 3 I show an arrangement comprising five rollers, and their supporting 125 brackets, utilizing a combination of the several bearings above described, adapted to the increased total width and varying inclination of the several rollers. In such construction, the outermost separable brackets 30 are somewhat higher relatively, the integral bracket 3^b is used between one outer roller and the next adjacent one, and compound brackets 3^a—33 are used for the other intervening supports. In such arrangement, it is immaterial whether the remov- 130

able bracket 33 to be at one side or the other of the integral hub bracket. It is desirable, however, that a removable bracket be provided for one end of each roller, so as to 5 facilitate easy removal and adjustment.

In Figs. 4, 5 and 11 I show a somewhat modified construction of compound supporting bracket consisting of a bracket extension 3^{aa} upwardly beyond hub 3 upon which 10 is secured the removable bracket by its back web 33^a lying against the sloping face of main bracket 3^{aa}. The latter is reinforced as at 49, and provided with a transverse bolt 35 by which side plates 36, 36, are secured 15 to the sloping back web 37. The supplemental bracket 33^a is slotted at the bottom for engagement of bolt 38, and its side cheeks 39, 39, are riveted to the side plates 36 as at 40. As an additional holding connection, the rear upper portions of side plates 36 are hooked over and secured by bolt 35 as indicated at 41.

A bearing boss or projection 42 extends rearwardly from bearing casing 9 against 25 a wedge 43 adjustably inserted between the back and such boss whereby the bearing and the roll spindle are maintained outwardly in proper operation position. The wedge 43 is preferably hooked over the top edge of 30 back plate of bracket 33^a, as at 44, with sufficiently tight fit to ensure against accidental removal. At the other side, the other bearing casing 9 bears against the rear top of the bracket 3^{aa} by its boss 42 and each casing 35 is supported by its side lugs 32 in the slotted openings 31 of the respective side cheeks.

In Fig. 7 I show a further modification in which the hub 3 extends upwardly by a middle web member 3^c to which are secured 40 the outer side plates 39^a by transverse bolts 35^a. Such side plates provide the embracing cheeks for the bearing casings and have the slotted openings 31 for reception and support of the lugs 32 thereof. The bearing casings, thus supported, are also braced 45 against endwise movement by their projections 42 engaging against opposite sides of the upper portion of the web 3^c.

In Fig. 6 I show a detail of a continuous 50 line pipe 16^a for lubrication, having branch pipe extensions 26^a and an intervening cock or valve 28^a with suitable couplings. By this means, a plurality of bearings 9 may be lubricated from a single pipe and any 55 particular pair of bearings may be cut out and the branch connections temporarily removed, if desired.

Figs. 12, 13 and 14 show a slightly modified construction utilizing individual supporting brackets 45, 46 and 47 extending upwardly from their respective hubs 3, and of right and left hand form to suit their respective locations. Each hub is freely mounted on rock shaft 2 for rotation or end- 60 wise movement, and normally controlled by

bearing collars 50, each having a tightening set screw, on shaft 20. By this arrangement, the whole series of rollers may be thrown back at once, or by removing the screws 23 from any particular pair of bearings 22, such pair of brackets 21 and their particular roller may be thrown back independently of the others, and one of the brackets may be shifted laterally to remove the roller. 70

By either construction, I am enabled to adjust the roller or rollers upwardly towards and in contact with the belt, or downwardly away therefrom, without stoppage or interference. The manner of mounting and supporting the several brackets ensures rigidity and stability of the roller structure when erected, and also facilitates the throwing of these elements backwardly and downwardly, with a minimum of friction and absence of interference or interruption to the continued operation of the carrier. 75

It will be understood that the bearing for rock shaft 2 is fixedly spaced from its companion bearing 18^a by a connecting base 90 plate 18^b by which the bearings are fixedly secured in such relation to the main framing structure 19.

One further feature of advantage is in the construction of the rollers A or B. 95 These are preferably made of tubular sections of pipe and are turned down around the beveled or rounded edges of the flanges of hubs 6, as indicated at 48. Such construction ensures concentric engagement and 100 continuous connection with the hubs, overcoming any tendency to loosening or disarrangement.

It will be understood that the invention may be variously changed or modified in detail construction, or otherwise, by the skilled mechanic in adapting it to various applications of use, but that all such are to be considered as within the scope of the following claims. 110

What I claim is:

1. Supporting mechanism for a carrying belt consisting of a rock shaft having bearing supports extending upwardly therefrom having bifurcated slotted arms and a belt 115 engaging roller carried thereby.

2. Supporting mechanism for a carrying belt consisting of a rock shaft having freely journaled bearing supports extending upwardly therefrom and provided with roller supporting brackets, a roller therein, and means limiting tilting movement of the roller brackets on the rock shaft. 120

3. Supporting mechanism for a carrying belt consisting of a belt supporting roller, brackets therefor, a freely journaled rock shaft for the brackets, and means for bracing the brackets in erected position and providing for backward tilting movement on the rock shaft. 125 130

4. In combination with a supporting framework, a transverse rock shaft, bearings therefor, brackets freely journalled on to the rock shaft extending upwardly therefrom and provided with supporting terminals, and a belt carrying roller mounted therein.
5. In combination with a supporting framework, a transverse rock shaft, bearings therefor, brackets freely journalled on to the rock shaft extending upwardly therefrom and provided with supporting terminals, shaft casings mounted in said terminals, and a belt carrying roller having a shaft mounted in said casings.
6. In combination with a supporting framework, a transverse rock shaft, bearings therefor, brackets secured to the rock shaft extending upwardly therefrom and provided with supporting terminals, and a plurality of rollers rotatably mounted in pairs of said brackets at varying inclinations.
7. In combination with a supporting framework and a superimposed carrier belt, a transverse rock shaft, brackets secured theron having upwardly extending roller-carrying arms and forwardly extending bracing arms, and a belt supporting rollers carried in said brackets.
8. In combination with a rock shaft, a bracket secured thereon having an upwardly extending bearing portion provided with bifurcated slotted arms.
9. In combination with a rock shaft, a bracket secured thereon having an upwardly extending bearing portion provided with bifurcated slotted arms, and a separable supplemental bracket.
10. A combination bracket for belt carrying rollers consisting of a hub having a lateral bracing portion, an upwardly extending bearing bracket, and an attached oppositely disposed removable bearing bracket.
11. A combination bracket for belt carrying rollers consisting of a hub having a lateral bracing portion, an upwardly extending bearing bracket, an attached oppositely disposed removable bearing bracket, and means for connecting and disconnecting said brackets.
12. In belt supporting construction, a shaft having flanged supporting hubs, and a tubular roller having crimped engagement at its ends inwardly around the outer edges of the hub flanges, substantially as described.

In testimony whereof I hereunto affix my signature.

FRANK E. SMITH.
